UNITED STATES PATENT OFFICE.

THEODORE B. SCHIMPFF, OF SCRANTON, PENNSYLVANIA.

TRICK KNIFE.

Application filed March 29, 1920. Serial No. 369,684.

To all whom it may concern:

Be it known that I, THEODORE B. SCHIMPFF, citizen of the United States, residing at Scranton, in the county of Lackawanna and State of Pennsylvania, have invented certain new and useful Improvements in Trick Knives; and I do hereby declare the following to be a full, clear, and exact description of the invention, such as will enable others skilled in the art to which it appertains to make and use the same.

This invention relates to the class of puzzles and magic and particularly to what are known as tricks, the main object of my invention being the provision of a trick in the form of an imitation knife wherein the blade is quickly and readily closed into the handle of the knife without the necessary manipulation of the blade by the use of the hand.

Another object of the present invention is the provision of a trick knife adapted to be held in the hand, with the blade open and grasping the handle near the pivoted end 25 of the blade and releasing the handle with the second mentioned hand quickly to thus convey a quick upward movement of the end of the handle to which the blade is pivoted whereby the blade will be quickly closed 30 into the handle.

A further object of the invention is the provision of a trick knife, the handle portion of which is held by one hand of the operator, while the other hand grasps the handle at the point where the blade is pivotally connected thereto by the thumb and forefinger of this hand and by grasping the blade at this point with the thumb and forefinger and quickly releasing the same by a 40 downward movement of the hand, the blade of the knife will be quickly moved to its closed position within the handle.

With the above and other objects in view, the invention consists in the novel features 45 and construction, the combination and arrangement of parts hereinafter more fully set forth, pointed out in the claim and shown in the accompanying drawings, in which—

Figure 1 is a longitudinal sectional view 50 of my improved trick knife, the blade being illustrated in an open position and in a closed position by the dotted lines, and

Figure 2 is a side elevation illustrating the 55 position of the knife with respect to the hands of the operator when it is desired to move the blade to a closed position.

In the general construction of my improved trick knife I provide a handle member generally indicated by the numeral 1, having a longitudinal groove 2 to receive the blade 3 when in a closed position. The handle 1 comprises a central enlarged body portion having at one end a reduced extension 4 terminating into a knob 5 at one end, while the other end terminates into a reduced neck portion 6 having a ferrule 7 mounted thereon which is adapted to reinforce the neck portion 6 and support the pivot pin 8 upon which the blade 3 is mounted.

The inner reduced end 9 of the blade 3 is arranged within the outer end of the groove 2 and loosely mounted upon the transverse pivot pin 8 so that the blade has a free movement when being swung to either an open or a closed position. Particular attention is directed to the fact that the blade 3 can be quickly moved to a closed position through any slight upward movement of the inner end of the handle.

In order to operate the knife so as to provide a suitable trick in the closing of the blade 3 without touching the same by the hands of the operator, the outer end of the handle portion is grasped by the left hand as illustrated in Figure 2 while the ferrule 7 is held between the thumb and forefinger of the other hand and by sufficient pressure and quick downward movement of the thumb and forefinger on the ferrule 7, the blade 3 will be caused to quickly fly shut or to a closed position as illustrated in dotted lines in Figure 2. The operator may, if he desires to cover the trick of closing the knife or to distract the attention of an audience, make believe blowing 95 the blade shut and, at the same time, quickly removing the thumb and forefinger from the ferrule 7 so as to thus cover the real operation of the trick. It will be apparent that as the thumb and forefinger are quickly withdrawn from the ferrule 7 by a slight snapping movement, the inner end of the handle will be vibrated upwardly giving a jerk to the blade 3 which will quickly throw the same to a closed position.

From the above description taken in connection with the accompanying drawings, it will be readily apparent that I have provided a simple and durable trick knife which can be operated with the minimum of practice by simply grasping the handle of the knife with the hands in the position set

forth above and by the manipulation of one of the hands quickly throw the blade 3 to its closed position within the groove 2 of the handle.

5 What I claim is:

A device of the class described including a handle provided with a longitudinal groove, a split reinforcing ferrule mounted on one end of the handle, a blade member having one end loosely mounted within one 10 end of the groove and normally arranged

within the groove when in a closed position, said blade extending in longitudinal alignment within the groove when in an open position whereby the blade is actuated to move the same to its normal closed position through a vibrating movement manually imparted to the handle at the pivot point of the blade.

15 In testimony whereof I affix my signature. 20

THEODORE B. SCHIMPFF.
